UNITED STATES PATENT OFFICE

137,777

DESIGN FOR A DEVICE FOR ERECTING AND SUPPORTING POLES

Francis L. Collum, Allentown, Pa.

Application July 17, 1943, Serial No. 110,676

Term of patent 14 years

(Cl. D41—1)

To all whom it may concern:

Be it known that I, Francis L. Collum, a citizen of the United States, residing at Allentown, in the county of Lehigh and State of Pennsylvania, have invented a new, original, and ornamental Design for a Device for Erecting and Supporting Poles, of which the following is a specification, reference being had to the accompanying drawing forming part thereof.

Fig. 1 is a perspective view of a device for erecting and supporting poles embodying my new design with the pole broken away to represent indeterminate length; and

Fig. 2 is a side view of Fig. 1.

I claim:

The ornamental design for a device for erecting and supporting poles, substantially as shown.
FRANCIS L. COLLUM.
